(57) **CLAIM**

The ornamental design for a beverage glass, as shown and described.

DESCRIPTION

FIG. 1 is a top perspective view of a beverage glass showing my new design;

FIG. 2 is a side view thereof;

FIG. 3 is a reduced scale top view thereof;

FIG. 4 is a reduced scale bottom view thereof; and,

FIG. 5 is a cross-sectional view showing a section taken along like 5-5 of FIG. 2.

The broken lines in the drawings depict portions of the Beverage Glass that form no part of the claimed design.
